UNITED STATES PATENT OFFICE.

EDWARD McGARVEY, OF BELLEFONTE, PENNSYLVANIA, ASSIGNOR TO INTERNATIONAL ELECTRIC COMPANY, OF BELLEFONTE, PENNSYLVANIA, A CORPORATION OF ARIZONA.

PRINTING MECHANISM FOR AUTOMATIC RECORDING-SCALES.

1,101,207.

Specification of Letters Patent. Patented June 23, 1914.

Application filed October 3, 1911. Serial No. 652,832.

To all whom it may concern:

Be it known that I, EDWARD McGARVEY, a citizen of the United States, residing at Bellefonte, in the county of Center and 5 State of Pennsylvania, have invented certain new and useful Improvements in Printing Mechanism for Automatic Recording Scales, of which the following is a specification.

10 My invention refers to the class of automatic weighing scales in which printing mechanism is utilized to record the result of each weighing operation, as accomplished by the usual beam and automatically controlled 15 poise thereon actuated by an electric motor, which in turn is controlled by the operation of the beam itself.

The printing mechanism comprises a series 20 of printing wheels in geared engagement with the motor actuated screw for feeding the poise, in combination with printing mechanism comprising a paper strip and inking ribbon, actuated to bring them into 25 contact with the previously located characters on the type wheels by the action of a separate motor and a controlling circuit therefor.

The subject of the present application refers 30 particularly to the actuating mechanism for these parts in its operative relation and in combination with the scale structure.

In the drawings illustrating the invention: Figure 1 is a view of the entire apparatus as applied to the poise beam of a scale and its 35 parts, in side elevation. Fig. 2 is an enlarged sectional detail view indicated by the line II. II. of Fig. 1. Fig. 3 is a plan view of the machine, further enlarged. Fig. 4 is a vertical sectional detail view showing the 40 arresting mechanism for the printing wheels, indicated by the sectional line IV IV of Fig. 3. Fig. 5 is an enlarged detail view showing the printing mechanism, paper carriers, motor, etc., in side elevation. Fig. 6 is an end view of the construction of Fig. 5. Fig. 7 is a plan view of Fig. 5. Fig. 8 is a vertical sectional detail view on the line VIII VIII of Fig. 3. Fig. 9 is a detail view in elevation, illustrating the actuating cam for 50 the printing platen. Fig. 10 is a sectional detail view of the printing mechanism, similar to Fig. 5, from the other side. Fig. 11 is a cross section through the paper winding

reel on the line XI XI of Fig. 10. Fig. 12 is a diagram of the wiring circuit, contact 65 mechanism, and branch circuit for actuating the motor for the printing mechanism. Figs. 13 and 14 are partial similar diagrams of the trig loop contact mechanism of the beam, in different positions. 60

In the drawings I have illustrated the invention as embodied with a weighing apparatus of the same type and construction generally as that illustrated in a companion application filed herewith. These show the 65 usual balancing beam 2 of a scale mounted by knife edge bearings 3 in any suitable support, as bearings 4, extending upwardly from the base of the scale frame. The beam 2 is in the form of a rectangular frame having 70 two oppositely arranged side bars joined at their ends by cross bars 5 and 6 of any suitable construction, the endmost bar 5 providing a bearing for the outer end of the poise feed screw and for mounting of the terminal 75 movable contact members, the inner end 6 also providing a bearing for the motor shaft.

7 is the adjustable poise mounted by supporting wheels 8 at each side on supporting tracks 9 arranged longitudinally of the beam 80 2 at each side of its central open clearance space, and having interfitting engagement with the screw 11 by suitable nut devices 10. Upon rotation of the shaft in either direction, poise 7 is located at its proper position 85 on the beam to balance it in the same manner generally as is the ordinary poise of the usual weighing scale or as is the poise of recording scales of this type.

The machine is designed to operate automatically so that the poise will be located at the proper position, depending upon the weight of the goods or article being weighed so as to bring the poise beam to a condition of rest in the shortest possible time. 90

The screw 10 is actuated by a motor M, the shaft 13 of which has a bearing in the outer end of the beam at 14 and is coupled at its inner end with an electro-magnet 15. 95

The printing mechanism, generally designated by the letter P, comprises a series of upper indicating or reading wheels and a series of lower printing wheels, the unit wheel of which is geared with the inner end of the screw shaft 11, the several wheels comprising each series being geared together, each 100 105

series being connected by intervening idler gears as more particularly hereinafter described. The extreme inner end of the screw shaft 11 is provided with a clutch disk 16, 5 adapted to be coupled with the magnet 15, for rotation of the screw shaft 11 and its actuating parts.

The operation of the motor M is controlled through contact mechanism located at the 10 outer end of the beam and illustrated in diagram in Figs. 11, 12 and 13, and more particularly set forth in the companion application above referred to.

For the purpose of the present application, it is sufficient to state that circuit to the motor M is established from the main line conductors A, B, by means of vibrating contacts 24, 25, mounted preferably on a pivoted sensitively supporting bar 26 at the 15 outer end of the beam 2, adapted to close the circuit in the raised position of the beam, as in Fig. 12, through contact 39, branch contact 30¹¹, wire 30¹ to main conductor B, and from contact 25 through conductor 42 to the 20 armature m of the motor, thence by conductor 41, contacts 24 and 40, branch conductor 30¹¹, wire 30¹ to the field F of the motor M, thence by conductor 44 to the other main line conductor A, for one direction of 25 the rotation of the motor. Reversely, in the lowered position of the beam, contact 24 closes circuit from main line conductor B through connection 30¹, wire 41 to the motor armature m, thence by wire 42, contacts 25 30 and 34, wire 30¹ to the fields F of the motor conductor 43 to clutch 15 and wire 44 to the other main line conductor A.

The series of printing wheels for making the impression upon the paper strip, are 40 located in axial alinement with the screw shaft 11, to which the unit wheel 17 is fixedly secured. The additional printing wheels, 18 are loosely mounted on the extension of screw 11 and automatically actuated by the 45 rotation of the first printing wheel 17 through automatically operative transmitting gearing 19 co-acting with a series of inter-engaging teeth 20 on the wheels 18, of well known construction, and similar to the 50 printing wheels 4 to 10 inclusive of my prior Patent No. 701757.

A series of indicating or reading wheels 21, having characters corresponding to those of the corresponding printing wheels 17-18, 55 is located upwardly above and in front of the printing wheels 17-18 within a surrounding casing 22 mounted on the frame and having an aperture through which the particular combination of figures of each 60 particular printing operation is observed.

Secured to the screw shaft 11, or to the pinion 20 of the unit wheel 17, is a star shaped arresting wheel 23. The purpose of 65 said wheel is to positively fix the position of the unit wheel 17, by the action of an enter-

ing point forming a portion of the operative mechanism. A supplemental additional arresting device is provided for the remaining wheels, consisting of a pivotally mounted plate 23^b, hinged at 23^c on the side member 70 of the beam, and provided with a plurality of fingers 23^d. Said plate is raised in unison with the point 23^a by means of a spring 23^e secured to the upper end of one of the sliding sleeves 23^f mounted on the guide studs 75 or pins 23^g. These pins are secured in and extend upwardly from a projecting supporting flange 2^a of the beam. (See Fig. 8.) The several printing wheels, as thus arranged and geared with the screw shaft, are 80 so arranged that they will form a combination of figures corresponding to the weight and the corresponding position of the poise at all times.

The mechanism for recording the particular weight indicated by the wheels at any position, consists of a strip of paper 27 which is wound from one paper reel 27^a to another similar reel 27^b intermittently for each printing operation, by means of a 85 ratchet wheel 27^c, actuated by a spring-retracted pawl 27^d, a similar locking pawl 27^e acting to arrest the reel against reversal. Said paper wheels together with the actuating mechanism therefor, the platen mechanism and the several co-acting parts, are mounted upon a base 28, which is slidably mounted on a runner plate 28^f having side bearing strips 28^g secured upon the frame of the machine, as indicated in Fig. 8, and 90 is fixedly located in its inner operative position by means of a removable securing pin 28^h. The base 28 is provided at one side with a rigid side portion or upright 28ⁱ in which are secured the studs 27^a and 27^b on which the paper reels are rotatably mounted. Each reel is retained in position by an outer washer and cotter pin, as shown, or by other suitable device and each is also normally pressed outwardly by a spring 27^j. Said 105 springs act to interpose sufficient friction during the partial rotation of the paper reels to prevent over-running of the reel at each intermittent pawl actuation.

On the base 28, extending upwardly from said plate 28 are the standards 28^k forming the vertical sliding bearings for the printing platen 28^l. Said platen is vertically reciprocable by means of a composite cam construction comprising outer cams or eccentrics 28^l, 28^m, with an inner or intermediate cam 28ⁿ. Printing platen 28^l rests by legs 28° on the outer cams 28^l and is provided at its upper portion with a supplemental pressure plate or platen 28^p. Said plate 28^p is mounted for independent movement, in addition to the movement of the main platen, by means of a stem 28^q extending centrally down through main platen 28^l and is provided with a bearing shoe 28^r resting on the 110 115 120 125 130

intermediate cam 28^e, and provided with a strap 28^f which surrounds said cam. (See Fig. 9.)

The platen 28^e is provided with guide stems 28^k extending down through receiving cavities in the standards 28^b. As thus constructed the platen 28^e is actuated by cams 28^d to raise and lower the paper strip 27 and a carbon ribbon 29, at each operation, toward and from the printing wheels. The actual impression of the carbon ribbon 29 and paper strip 27 against the several printing wheels is accomplished by cam 28^e at its highest point, acting to raise the supplemental platen 28^e slightly above its normal bearing on the top of the platen 28^e, such action being effected by the high point of cam 28^e. The withdrawal of the composite platen is effected through strap 28^f. Carbon ribbon 29 is mounted on receiving and delivering reels 29^a, 29^b, each of which is provided with a ratchet wheel 29^c; one of said ratchet wheels being actuated by the reversible pawl 29^d. The operation of said pawl is to intermittently feed the carbon ribbon for each printing operation and the pawl is reversible as indicated in dotted lines in Fig. 10, whereby to reverse the ribbon feed as will be readily understood.

The carbon ribbon reels are mounted on supporting studs 29^{a'} and 29^{b'}, extending inwardly from supporting plate 28^{'''} like studs 27^{a'} and 27^{b'}, and each is provided with a friction creating spring 29^e for the same purpose. Pawl 29^d is pivoted at 29^e to a sliding block mounted around or upon one of the standards 28^b and normally pressed upwardly by a spring 29^g. Said standard 28^b is provided at its upper portion with limiting pin 29^h extending into a limiting slot 29ⁱ of the sliding block 29^j. Said sliding block is, by the pin and slot, limited as to its upward movement under action of spring 29^g, and extends upwardly sufficiently far to be engaged by the head of platen 28^e at the last part of the downward movement, sufficiently far to lower the pivotal mounting 29^j of pawl 29^d, to engage one tooth of ratchet wheel 29^c. By this means it will be seen that the carbon ribbon is progressed slightly at each operation by limited action of spring 29^g to insure the impression on the paper strip. Similarly mounted upon or around the other standard 28^b is a sliding block 23^h resting upon a cushioning spring 23ⁱ which in turn rests upon a bracket 23^j which extends outwardly from one leg of the reciprocating platen 28^e. Extending upwardly from block 23^h or formed integrally with it, is a lifting dog 23^k adapted to abut underneath the centering point 23^a, and to raise it upon its guiding stems 23^g, at the same time effecting uplift of the plate 23^b and its arresting fingers. The purpose of cushioning spring 23ⁱ is to

provide elasticity to insure centering of the point 23^a in the alining star wheel 23, without binding. By these several means, it will be seen that the printing wheels having been located in position with any slight variation in alinement remaining for correction by the star wheel adjustment, upon actuation of the reciprocating platen 28^e upon feed of the paper strip 27, carbon ribbon 29, actuation of the star wheel 23, raising of the main platen 28^e to bring the paper strip and carbon ribbon in operative relation to the printing wheels, and the final supplemental upward pressure of the supplemental platen 28^e, will effect the printing of the number indicating the weight on the paper strip. As arranged, it is designed that these operations shall be performed after the poise beam has come to rest, by the independent operation of an electric motor and controlled through a separate switch and circuit connections by the attendant. For such purpose an electric motor M' is mounted upon the plate 28 and its shaft m' is provided with a worm m² meshing into a worm wheel m³ on the end of shaft m⁴ carrying the cams 28^d—28^e for actuation thereof. Said worm wheel m³ is provided with a pin m⁵ which, at each rotation of the worm wheel, presses against the pivotally mounted leg 27^d of spring retracted pawl 27^d, for actuation of the paper strip winding reel 27^e.

It is designed that current shall be established to the motor from any suitable source of current as by main conductors A, B, through the operation of a manually controlled switch s. A make and break contact mechanism consisting of a rotating disk m⁶ having an interrupted annular conductor and intervening insulation is mounted on the other end of shaft m⁴, whereby to provide for automatic break of the circuit from the motor M'. In the normally inoperative and stationary position of the printing mechanism, circuit is broken through the connections to the motor, as illustrated in the diagram of Fig. 12. Thus by a branch conductor x to spring contact m⁷ resting on the insulating segment m⁸ of wheel m⁹ there is no current passing to the motor, but by closing the spring retracted switch s, circuit is closed through branch conductor y' to the motor, which is connected at the other side by conductor z with the main line conductor B. Upon current thus being established, the motor will operate to perform one rotation of shaft m⁴ accomplishing the printing operation. Retraction of the spring switch s, which is but momentarily closed, breaks the circuit to the motor, which has been set up through the current from the conductor x, spring contact m⁷ and annular conductor m⁹ of wheel m⁹ and branch conductors y' at the termination of one complete revolution of the insulating wheel m⁹.

The motor then comes to rest, its momentum being counteracted by the braking effect of a magnetically controlled armature brake ¹⁰ actuated by a pressure spring and retarding magnet, of well known construction, interposed in the circuit.

The printing operation is effected through the means just described at the termination of each weighing operation, and the results are noted upon the paper strip in continuous series of figures consecutively throughout its length, thus providing a positive record of any number of weighing operations.

15 By my construction I avoid the presence or necessity of any mechanical connection between the poise beam and its associated parts and the printing mechanism, so that each operation is independent of the other.

20 This is a highly desirable feature in scales of this type.

The construction and operation of the apparatus will be readily understood from the foregoing description.

25 The mounting of the reciprocating platen and its several connected parts on the slidingly arranged base 28, to which the conducting wires may be flexibly connected, renders it easily possible to withdraw the printing mechanism for removal or renewal of the paper strip or carbon ribbon, or of any other parts.

30 The apparatus may be changed or varied in construction or design in various features of detail by the skilled mechanic but all such changes are to be considered as within the scope of the following claims.

What I claim is:

1. In a recording scale, the combination with a poise beam, a poise thereon, a feed screw mounted on the beam and threaded into the poise, a motor on the beam operatively connected with the feed screw, and printing wheels operatively connected with the screw in axial alinement therewith; of independently operative printing mechanism for making a record from the printing wheels embodying a primary and a secondary platen actuating means therefor, and an independent motor for said means.

2. In a recording scale, the combination with a poise beam, a poise thereon, a feed screw mounted on the beam and threaded into the poise, a motor on the beam operatively connected with the feed screw, and printing wheels operatively connected with the screw in axial alinement therewith, of mechanism for locating a record and carbon strip across the printing wheels, and a combined reciprocable primary and secondary platen adapted to press said strips against said wheels.

3. In a recording scale, the combination with a poise beam, a poise thereon, a feed screw for the poise mounted on the beam, a

motor on the beam operatively connected with the feed screw, and printing wheels operatively connected with the screw, of mechanism for locating a record and carbon strip across the printing wheels, and a reciprocable platen embodying a supplemental pressure platen adapted to adjust the strips to operative position in relation to the printing wheels.

4. In a recording scale, the combination with a poise beam, a poise thereon, a feed screw for the poise mounted on the beam, and printing wheels operatively connected with the screw, of mechanism for locating a record and carbon strip across the printing wheels, a reciprocable platen adapted to press said strips against the printing wheels, cam actuating mechanism therefor, and a motor for operating said cam mechanism.

5. In a recording scale, the combination of a poise beam, a poise, a feed screw engaging the poise, a printing platen, and printing wheels operatively connected with the screw; of a ribbon reel having a printing ribbon in operative relation to the printing wheels, a ratchet wheel, a sliding block in operative relation to the printing platen, a pawl pivoted on said block and engaging said ratchet wheel, a spring normally pressing said block upwardly, and means for actuating the sliding block substantially as set forth.

6. In a recording scale, the combination of a poise beam, a poise, a feed screw engaging the poise, a printing platen, and printing wheels operatively connected with the screw; of a pair of ribbon reels each having a ratchet wheel and adapted to present a printing ribbon in operative relation to the printing wheels, a sliding block in operative relation to the printing platen and adapted to be depressed thereby, a reversible pawl pivoted on said block and adapted to engage either ratchet wheel, a spring normally pressing said block upwardly, and means for actuating the sliding block, substantially as set forth.

7. The combination with a poise beam of a scale having a poise and a screw shaft engaging the poise, printing wheels including a unit wheel connected with the screw shaft, and a reciprocable platen; of an arresting star wheel for the unit printing wheel, a reciprocable interlocking finger therefor, and a lifting dog for said finger in operative engagement with the reciprocable platen.

8. The combination with the screw shaft of a scale beam and printing wheels connected with the screw shaft provided with gearing, of a series of reciprocable interlocking fingers adapted to engage said gearing and means for actuating said fingers.

9. The combination with the screw shaft, of a scale beam and printing wheels connected with the screw shaft, of a star wheel,

- and actuating gearing associated with the printing wheels, and a plurality of recipro-
cable interlocking fingers adapted to make engagement therewith.
- 5 10. The combination with a poise beam of a scale having a poise and a screw shaft engaging the poise, printing wheels includ-
ing a unit wheel connected with the screw shaft, and a recipro-
cable platen; of an ar-
10 resting star wheel for the unit printing wheel, a recipro-
cable interlocking finger therefor, a recipro-
cable printing platen having a co-acting lifting device for said finger, and a cushioning spring for said finger.
- 15 11. The combination with the screw shaft of a scale beam and printing wheels connected with the screw shaft, of an arresting star wheel for the unit printing wheel, a recipro-
cable interlocking finger therefor, and
20 a recipro-
cable printing platen having a co-
acting lifting device for said finger, and a cushioning spring for said lifting device.
12. The combination with the screw shaft of a scale beam and printing wheels con-
25 nected with the screw shaft, of a star wheel, guiding pins, a recipro-
cable finger having sleeves mounted thereon, and a recipro-
cable printing platen having a co-acting lifting device for said finger.
- 30 13. The combination with the screw shaft of a scale beam and printing wheels connected with the screw shaft, of a star wheel and actuating gearing associated with the printing wheels, guide pins, a recipro-
35 cable finger for the star wheel having sleeves mounted on said pins, a series of interlocking fingers for engaging the printing wheel gearing, and means connected to one of said sleeves for actuating said fingers.
- 40 14. The combination with the screw shaft of a scale beam and printing wheels connected with the screw shaft, of a star wheel and actuating gearing associated with the printing wheels, guide pins, a recipro-
45 cable finger for the star wheel having sleeves mounted on said pins, a series of interlocking fingers for engaging the printing wheel gearing, and a spring connecting said fin-
gers with one of said sleeves.
- 50 15. In a scale, the combination with the

poise beam, a poise thereon, a feed screw for the poise mounted on the beam, a motor on the beam operatively connected with the feed screw, circuit establishing contact mechanism operable by the beam, and main 55 conductors; of printing mechanism comprising a recipro-
cable platen, a carbon ribbon and a paper strip, winding mechanism therefor, means for actuating the platen and said winding mechanism, a motor geared 60 with said actuating means, and circuit connections from said main conductors for said motor.

16. In a scale, the combination with the poise beam, a poise thereon, a feed screw for 65 the poise mounted on the beam, a motor on the beam operatively connected with the feed screw, circuit establishing contact mechanism, and main conductors; of printing mechanism comprising a recipro-
cable 70 platen, a carbon ribbon and a paper strip, winding mechanism therefor, means for actuating the platen and said winding mechanism, a motor geared with said actuating means, circuit connections from said main 75 conductors for said motor, and an interposed switch for said motor circuit.

17. In a scale, the combination with the poise beam, a poise thereon, a feed screw for the poise mounted on the beam, a motor on 80 the beam operatively connected with the feed screw, circuit establishing contact mechanism, and main conductors; of printing mechanism comprising a recipro-
cable platen, a carbon ribbon and a paper strip, 85 winding mechanism therefor, means for actuating the platen and said winding mechanism, a motor geared with said actuating means, circuit connections from said main conductors for said motor, an interposed 90 switch for said motor circuit, and make and break mechanism interposed in said branch circuit.

In testimony whereof I hereunto affix my signature in the presence of two witnesses. 95

EDWARD McGARVEY.
